US00D720663S

(12) **United States Design Patent**
Spalding et al.

(10) **Patent No.:** US D720,663 S
(45) **Date of Patent:** ** Jan. 6, 2015

(54) **WHEELCHAIR**

(75) Inventors: **Joseph Spalding**, Akron, OH (US);
Daniel James Yee, Parma, OH (US);
Traian Mohan, Parma, OH (US);
Damon Jurkiewicz, Cleveland, OH (US)

D333,737 S 3/1993 Adams
